COIN DETECTING APPARATUS

Albert E. Gebert, Wilmette, and Floyd C. Black,
Chicago, Ill., assignors to Advance Machine
Company, Chicago, Ill., a corporation of Illinois

Application July 1, 1938, Serial No. 216,918

4 Claims. (Cl. 194—101)

This invention relates to improvements in coin detecting or selecting mechanism, particularly adapted, though not necessarily limited in use for vending or coin actuated mechanisms which 5 require the deposit of a coin or check to render the same operative.

In devices of this character it is customary to provide a chute or runway along which the coin or check travels before it is deposited or delivered 10 into the operating mechanism to render the latter active, and to also provide mechanism arranged adjacent the path of travel of the coin or check along such runway to separate the improper checks, coins or tokens from the proper 15 ones, so that the latter will be delivered into the machine while the improper ones will be rejected or prevented from entering the operative mechanism of the machine, or returned to the operator.

20 It is one of the objects of the present invention to provide an improved detecting mechanism in which the coins to be separated will roll along on their edge past a magnet or between two magnets, or through a magnetic field, in a manner 25 that the magnet can exert its influence upon the coins.

It has been found that the speed of travel of the coins or checks along the runway or chute is influenced by the nature and weight of the coin 30 and this in a measure influences the operation of the detector.

It is a further object of the invention to provide in a device of this character improved means 35 to effect a partial detection of the coins before they are delivered into the chute or runway to be further detected during their travel therewith, such means also operating to deposit the coins or checks into the chute or runway at substantially the same point and from a point in 40 proximity thereto, so that the impetus of all of the coins or checks along the runway through the magnetic field and at the point where they are delivered from the chute will be substantially the same, with the result that a more effective 45 separation or detection will result.

A further object is to provide improved means for obtaining an effective separation or detection of the coins even though the mechanism should be tilted.

50 To the attainment of these ends and the accomplishment of other new and useful objects as will appear, the invention consists in the features of novelty in substantially the construction, combination and arrangement of the several parts hereinafter more fully described and

claimed and shown in the accompanying drawing illustrating this invention and in which

Figure 1 is a view partly in front elevation, partly in section, and with parts omitted, of a device of this character constructed in accordance with the principles of this invention. 5

Figure 2 is a view similar to Figure 1 with other parts omitted.

Figure 3 is a sectional view taken on line 3—3, Figure 1, with parts omitted. 10

Figure 4 is a sectional view taken on line 4—4, Figure 3.

Figure 5 is a view similar to Figure 1 showing the mechanism tilted.

Referring more particularly to the drawing, 15 the numeral 10 designates generally a runway or chute along which the coins are adapted to travel and to roll on their edge, the runway being provided with a bottom portion 11 which preferably terminates a considerable distance short 20 of the end 12 of the side members of the runway.

Opposed magnets 13 are arranged on opposite sides of the runway and are supported in any suitable manner such as by supporting members 14, the poles or free ends of the magnets projecting through openings 15 in the walls of the runway. 25

This runway is arranged in an inclined position and may be supported in any desired or suitable manner. 30

Adjacent the discharge end of the runway and arranged therebelow is a member provided with an upright portion 16 and a laterally projecting portion 17, the latter being preferably downwardly inclined while the upper edge 18 of the 35 portion 16 is reduced or beveled.

This member 17 is swingingly supported below the outlet end of the chute, in any suitable manner preferably by means of a member 19 secured thereto and pivotally supported at its upper end 40 as at 20.

A stop 21 may be provided for limiting the swinging movement of this member in one direction.

The coins when they are deposited into the 45 runway will strike the bottom 11 and will roll therewith past the magnets 13 and will drop out of the open end of the runway so as to fall upon the members 16—17.

The coins passing along the runway must pass 50 between the poles or magnets 13, and the current, the intensity of which varies according to the nature of metal or material of the coin or slug, has the effect of retarding the motion of the coins so that they will drop out of the coin 55

chute or runway with more or less speed or momentum.

This speed, however, up to the point where they enter the magnetic field is controlled according to the point at which the coin is deposited into the chute. Therefore, it is desirable to deposit all of the coins in the chute at the same point with reference to the magnetic field so that the heavier coins will not acquire a greater speed than the lighter coins, which might affect their passage through the magnetic field.

Therefore in order to deposit these coins and start them along the chute at substantially the same point, any suitable mechanism may be provided for that purpose, and which mechanism itself is adapted to partially separate or detect the coins. A suitable and efficient mechanism for this purpose is shown and described in United States Patent #1,452,721 issued April 24, 1923, to Alfred D. Antoine.

Suffice it to say that such mechanism embodies a check or coin carrier 22 having a coin seat 23 therein and which is adapted to be rotated by means of an operating handle 24 secured to a shaft 25 to which the coin carrying disc 22 is connected. Arranged adjacent the path of movement of the coin in the check seat 23 is a mechanical detector mechanism 25 and arranged also adjacent the path of movement of the coin in the seat 23 is a magnet 26 so positioned that magnetic coins will be prevented from being discharged from the check seat into the runway. The mechanical detector means 25 will also detect and prevent other spurious coins from being delivered into the check chute or runway 10, all as described in the aforesaid patent.

When the check carrying disc 22 is in the position shown in Figure 2, the coin will be delivered or discharged therefrom and will drop into the coin chute or runway upon the bottom 11 at a point in proximity to the magnets 13. Therefore, it will be seen that all of the coins or checks which pass through the initial separator will drop upon the bottom 11 of the runway at the same point with respect to the magnets 13. Therefore, the momentum of these respective coins will start from the same point with the result that the coins will all roll with substantially the same speed or momentum to the point where they enter the magnetic field.

The proper coins such as indicated at 27 in Figure 2 will drop off of approximately at the end 28 of the bottom 11 of the coin chute and will fall upon the edge 18 of the member 16 to be discharged into the pocket 30.

All of the improper coins or tokens as indicated at 29 will pass off of the bottom 11 of the coin chute at the end 28, and their trajectory will cause them to fall upon either the edge 18 of the member 16 or on the inclined member 17 to be returned to the operator or prevented from entering the machine to operate it.

It will therefore be manifest that with this improved apparatus the coins will be partially detected or separated as they are passing through the initial mechanism in which the check carrying disc 22 is arranged. The coins which pass the magnet 26 and the mechanical detector 25 will be discharged into the coin chute or runway 12 and will roll on their edge through the magnetic field to be separated by the latter.

In the event that the mechanism is tilted as shown in Figure 5, the members 16-17 which are swingingly supported by the member 19 will assume the position shown in Figure 5 which will

prevent any of the coins from entering the dispensing mechanism of the apparatus.

While the preferred form of the invention has been herein shown and described, it is to be understood that various changes may be made in the details of construction and in the combination and arrangement of the several parts within the scope of the claims, without departing from the spirit of this invention.

What is claimed as new is:

1. A coin selecting mechanism for separating coins and like metallic disc shaped elements, embodying an inclined chute along which they travel, means adjacent the path of travel of the same in the chute to provide a magnetic field to control their speed of travel, means whereby the coins may be deposited into the chute in advance of said magnetic field, a pendent member disposed adjacent the delivery end of the chute and mounted for free swinging movement, and an abutment surface on said member disposed below the bottom of the chute and in advance of the delivery end of the said bottom, and upon which abutment the coins fall after they have left the chute, said member and abutment operating to direct predetermined coins to travel to one side or the other of said abutment.

2. A coin selecting mechanism for separating coins and like metallic disc shaped elements, embodying an inclined chute along which they travel, means adjacent the path of travel of the same in the chute to provide a magnetic field to control their speed of travel, means whereby they may be deposited into the chute in advance of said magnetic field, a pendent member disposed adjacent the delivery end of the chute and mounted for free swinging movement, an abutment surface on said member disposed below the bottom of the chute and in advance of the delivery end of the said bottom, and upon which abutment the coins fall after they have left the chute, said member and abutment operating to direct predetermined coins to travel to one side or the other of said abutment, and a laterally projecting portion on said member below the said abutment surface and of a substantial area for receiving the coins from said abutment and guiding them in one direction.

3. A coin selecting mechanism for separating coins and like metallic disc shaped elements, embodying an inclined chute along which they travel, means adjacent the path of travel of the coins in the chute to provide a magnetic field to control their speed of travel, means whereby they may be deposited into the chute in advance of said magnetic field, a pendent member disposed adjacent the delivery end of the chute and mounted for free swinging movement, an abutment surface on said member disposed below the bottom of the chute and in advance of the delivery end of the said bottom, and upon which abutment the coins fall after they have left the chute, said member and abutment operating to direct predetermined coins to travel to one side or the other of said abutment, and a stop for limiting the pivotal movement of said pendent member in one direction, said member when in normal position operating to direct predetermined coins to travel in different directions, but when in an abnormal position with respect to the chute, operating to direct all of the coins to travel in the same direction.

4. A coin selecting mechanism for separating coins and the like metallic disc shaped elements, embodying an inclined chute along which they

travel, means adjacent the path of travel of the same in the chute to provide a magnetic field to control their speed of travel, means whereby they may be deposited into the chute in advance of said magnetic field, a pendent member disposed adjacent the delivery end of the chute and mounted for free swinging movement, and an abutment surface on said member disposed below the bottom of the chute and in advance of the delivery end of the said bottom, and upon

which abutment the coins fall after they have left the chute, said member and abutment operating to direct predetermined coins to travel to one side or the other of said abutment, the said abutment surface of the pendent member extending in a direction transverse to the said chute and being reduced to form a substantially narrow edge with which the coin contacts.
